UNITED STATES PATENT OFFICE.

EWALD LEIMBERG, OF BERLIN, GERMANY.

RAZOR-BLADE-SHARPENING APPARATUS.

Application filed January 15, 1925. Serial No. 2,630.

To all whom it may concern:

Be it known that I, EWALD LEIMBERG, a citizen of the German Republic, and resident of Berlin, Germany, have invented a new and useful Improved Razor-Blade-Sharpening Apparatus, for which I have filed application for a patent in Germany on August 9, 1923, and of which the following is a specification.

10 My invention relates to an apparatus for grinding and honing razor-blades of the kind which can be ground and honed at each of its two longitudinal edges and on both sides of each edge, first the grinding 15 and then the honing being effected successively at all four shaving edges. More especially, my invention relates to grinding and honing apparatus of the kind mentioned in which the blade is to be attached 20 to a holder carried at each end in a supporting member secured to the free ends of a U-shaped operating member which is reciprocated in a frame or casing carrying 25 on its bottom an obliquely arranged and exchangeable grinding body, or honing body respectively, over which the blade-holder with the blade is moved to and fro parallelly to itself; the holder with the blade being caused to rotate practically for 90° at 30 the end of every path and the direction of the successive partial rotations being always the same so that the two edges are ground, or honed respectively, in continuous alternation and on both sides of each edge. 35 There are in such an apparatus, of course, means for effecting the successive part-rotations, and my invention relates to these means. In the known apparatus mentioned, as well as in my improved one, the blade- 40 holder is provided at one end with two projections extending in opposite directions, parallelly to the breadth of the blade, and with two other projections extending at right angles thereto and cooperating with a 45 spring, or an equivalent therefor, by which the blade-holder and the blade are retained in their position after each change thereof. The consecutive changes of the position are effected by a stationary ledge-like guide 50 secured to the bottom of the casing or frame. In the known apparatus mentioned, said spring, or, may be, a rigid or comparatively rigid ledge which is subject to the action of separate springs provided at its ends, ex-

tends along parallelly to the first-mentioned guide-ledge and is lifted a little vertically alternately by one and the other of the before-mentioned projections, of which has been explained that they co-operate with a spring.

Now, in contradistinction to said known arrangement and combination of parts, as regards the spring and the parts co-operating therewith, the spring etc. are, in my improved apparatus, combined with the blade-holder and travel with it along to and fro, whereby the advantage is obtained that the pressure with which the shaving-edge to be ground and honed is pressed onto the respective body is always the same, or uniform respectively, whereas it is non-uniform in the known apparatus so that the shaving-edges are not uniformly ground and honed along the entire length of each side of each edge.

Another drawback of the known apparatus mentioned consists therein that the longitudinally extending spring, or its equivalent, and the blade-holder projections co-operating therewith get disengaged, in that said spring etc. glides off laterally from the respective projections whereby the apparatus is rendered inoperative at least for the time being. The owner is, however, not always able to replace himself the spring into its proper position.

In the whole, the improved apparatus is simpler and more reliable in action, and its operative parts are more easily accessible so that it is also more easily possible to remove inaccuracies that may arise in the guide-means or in the means for turning the blade-holder with the blade successively for about 90°, as described.

My invention is illustrated by way of example in the accompanying drawing in which Figure 1 is a perspective illustration of the complete apparatus; Figure 1^a is a vertical cross-section through the casing, opposite the end of the blade-holder (d), and Figures 2, 3, 4, and 5, are illustrations of the parts located within the casing at the top of Fig. 1 (rear end of inner side of apparatus on the left), and show various positions of these parts while the blade-holder with the blade is moved once to and fro.

The casing *a* which is practically U-shaped in cross section carries on its bottom

the grinding-body a' , or the honing-body respectively, which is arranged obliquely in known manner, as shown (Fig. 1). The upper rims of the sides of the casing are bent 5 round so as to form guides for a U-shaped slide b which consists preferably of wire and the free middle part of which serves as handle for operating the apparatus. To the end of each leg of the slide b is secured 10 a downwardly extending member c which serves as bearing for an end of the blade-holder d . The two ends of the blade-holder are differently long. The longer end carries the two projections, or, more precisely, 15 the two pairs of projections, mentioned in the preamble, e denotes one of these pairs, f the other. e is formed by a small ledge extending parallelly to the blade o which is attached in known manner to the holder d , 20 and f is formed by two bent ledges which are so shaped and connected with each other as to represent a rhomb. The long axis of the latter extends at right angles to the pair of projections e . 25 The rhomb f co-operates with a plate-spring g , or, more precisely, the four sides of the rhomb co-operate successively with said spring, which is held in place by two spiral springs $h h'$, either of which is connected at its upper end with one end of the plate-spring g and at its lower end with 30 one of two lugs $k k'$ forming parts of longitudinal projections of the respective bearing for the respective end of the blade-holder d . 35 Below the just described parts commences a ledge i which is provided with a curved projection i' at this end and extends in the direction to the handle-part of the slide b . The ledge i is firmly attached to the bottom 40 of the casing. Near its front end, between this latter and the lefthand sidewall of the casing, is an oblique projection j , which co-operates with the rhomb f , whereas the projection i' of the ledge co-operates with the 45 pair of projections e .

1 and 2 denote the shaving edges of the blade.

The manner of operation of the apparatus is as follows:

50 Supposing, a blade o be attached to the holder d , and the slide b drawn in the direction to the front of the casing; then that projection e which is the lower at the time being will push upon the oblique rear edge 55 at the end of the ledge i and will be turned thereby when gliding upwards on it, whereby also the rhomb f is turned and the springs g , h and h' are put under tension. At the 60 same time the blade-holder with the blade is so turned as to assume an oblique position. When the projection e in question has arrived on the top of the projection i' of the ledge i , that edge which is the lower one at the time being is just over the rear end of 65 the sharpening body a' , and when said pro-

jection e gets down upon the ledge while the slide is further drawn forwards together with the parts connected with it, the blade-edge mentioned gets down upon the body a' and is now drawn along over this body so 70 that every part of the edge in question is subjected to the action of that body.

When the blade-edge has arrived over the end of the sharpening body a' , the projection e has arrived at the projection j , contacts therewith, and is turned by it, so that also the blade-holder is turned and the blade-edge is lifted off the body a' . When now the slide b is drawn rearwards still a little more, the projection e is retained by the projection j and the rhomb f is turned from the position shown in Fig. 3 into the position shown in Fig. 4. Fig. 3 shows the parts in that position which they occupy when the lower projection e has just left the projection i' of the ledge i . They remain in this position until the rhomb f is being turned by the projection j . Figure 4 shows the parts concerned already moved away a little from the projection, j , viz on their way back to the rear end of the casing. When the rhomb has been turned in the manner described, the two projections e have changed their position, the formerly lower one being now the upper one, and the parts remain now in this position while they are moved towards the rear end of the apparatus. The now lower projection e having arrived at the projection i' of the ledge i 80 glides upon the projection whereby the three springs are again put under tension and the blade holder is so turned that the blade-edge is lifted off the sharpening body a' . Immediately thereafter the projection e in question gets upon the sloping end edge of the ledge i , in consequence whereof the rhomb f is turned for another quarter of a circle, but owing to the inertia of the quickly moving parts, the blade-holder with the blades assumes the position shown in Fig. 5, 85 which is no other position than the initial position shown in Fig. 2, the only difference being that now (Fig. 5) the blade-edge 2 is the lower edge of the blade whereas in Fig. 2 it is the upper one. The slide b is then again drawn out of its guideways so that the motions occurring during its path are repeated, and when the rhomb f has been turned for the second time, (by the projection j , the first turning having been effected by the projection i'), the slide is moved again back in the opposite direction, and the movable parts in general and the blade in particular are reciprocated in this way 90 until first the grinding and then the honing has been completed, the grinding body being exchanged for the honing body as soon as the grinding has been done.

It is obvious that the pressure with which the blade-edge is pressed onto the body a' is 95

always the same, i. e. uniform, and that it is out of the question that the rhomb *f* and flat spring *g* can ever come out of contact.

I claim:

- 5 1. In an apparatus for sharpening razor-blades at both edges and at both sides of each edge, in combination: a slide adapted to be reciprocated in a casing; blade-holder bearings at the free ends of said slide, and
- 10 a blade-holder supported in said bearings; two pairs of projections arranged at right angles to one another and attached to said blade-holder at one end thereof; a plate-spring carried by the bearing adjacent to said projections and arranged to cooperate with one of said pairs of projections and bearing on one of these latter; two spiral-springs connected at one end with the ends 35 of said plate spring and at the other end with said latter bearing; a guide-ledge on the bottom of said casing, and a stationary projection near the outer end of said ledge and adapted to co-operate with the other pair of projections, substantially as set forth.
- 15 20 with the other pairs of projections, substantially as set forth.

2. In an apparatus for sharpening razor-

blades at both edges and at both sides of each edge, in combination: a slide adapted to be reciprocated in a casing; blade-holder bearings at the free ends of said slide, and a blade-holder supported in said bearings; two pairs of projections arranged at right angles to one another and attached to said blade-holder at one end thereof; a 30 plate-spring carried by the bearing adjacent to said projections and arranged to cooperate with one of said pairs of projections and bearing on one of these latter; two spiral-springs connected at one end with the ends 35 of said plate spring and at the other end with said latter bearing; a guide-ledge on the bottom of said casing, and a stationary projection near the outer end of said ledge and adapted to co-operate with the other 40 pair of projections, substantially as set forth.

In witness whereof I have hereunto set my hand.

EWALD LEIMBERG.
